UNITED STATES PATENT OFFICE.

EMERY E. DAVIS, OF ST. LOUIS, MISSOURI, ASSIGNOR TO DAVIS BORING TOOL COMPANY, OF ST. LOUIS, MISSOURI, A CORPORATION OF MISSOURI.

EXPANSION REAMER.

Application filed October 27, 1922. Serial No. 597,300.

This invention relates to reamers and more particularly to reamers of the expansion type.

One of the objects of this invention is to provide an expansion reamer in which the blades are arranged for expansible adjustment and which shall be provided with novel means for rendering such adjustment permanent.

Another object of this invention is to provide a reamer in which the sliding blades are equipped with means for locking the blades effectively in adjusted position.

Further objects will appear from the detail description taken in connection with the accompanying drawing, in which:

Figure 1 is a longitudinal view, partly in section, showing a reamer head embodying this invention;

Figure 2 is a section on line 2—2, Figure 1;

Figure 3 is a partial end view showing the method of locking the blades;

Figure 4 is a section on line 4—4, Figure 3;

Figure 5 is a section on line 5—5, Figure 4; and

Figure 6 is an enlarged detail perspective illustrating the arrangement of the locking pins.

In the embodiment of this invention illustrated in the drawing, 1 designates a reamer head which is usually cylindrical in shape and is provided with a bore 2 adapted to receive a shank for mounting the same in a machine or holder and with clutching means, such as the notch 3, adapted to receive a dog on the shank to provide a driving connection. The head 1 is provided with a series of blade receiving slots 4, the bottoms 5 of which are inclined outwardly toward the tip of the head. A series of blades 6 is provided, each of which fits into one of the slots 4 so as to be slidable therewith. The lower edge 7 of each blade is beveled to a degree corresponding to the incline of the bottom 5 of the slot 4 so that when the blade 6 rests with its bottom edge 7 against the bottom 5 of the slot, the outer cutting edge 8 will be practically parallel with the axis of the reamer. By means of this arrangement the blades may be expanded by moving them along the slots 4 toward the tip of the reamer.

The body of the reamer 1 is provided with

a suitable thread 9 upon which an adjusting ring or collar 10 is adapted to turn. The collar 10 is provided with a radial face adapted to engage the radially disposed faces 11 of the heels of the blades 6. The ring 10 bears against the heels of the blades and provides an abutment for adjusting said blades along the slots 4. By turning the ring 10 on the thread 9 the blades may be moved forward or toward the tip of the cutter and along the slots 4 and by such movement, the cutters are expanded. A backing ring 12 may be threaded on the thread 9 and screwed up to engage the adjusting ring 10 so as to secure said adjusting ring in adjusted position. Suitable sockets 13 may be provided for the engagement of wrenches for turning the rings 10 and 12.

In order to hold the blades in adjusted position in the head, standard taper pins 14 are provided. Each of these pins is adapted to engage a groove 15 in the corresponding blade 6. The arrangement of the pins 14 is shown in detail in Figures 5 and 6. Figure 6 has been drawn to a somewhat enlarged scale and the angles of the pins and slots have been somewhat exaggerated so as to show the construction more clearly. Each pin 14 is adapted to fit into a taper groove 16. This groove is provided by drilling a taper hole in the head 1 at an angle both with the axis of the reamer and with the plane of the blade 6. This taper groove 16 is so adjusted that the intersection between its wall and the wall of the slot 4 provides an edge 17 which is parallel to the bottom 5 of the slot 4 and an upper edge 18 which makes an angle therewith. The groove 16, however, comprehends the major part of a circle, so that when the pin 14 is driven therein, it will be held in position, while projecting into the slot 4. Each blade 6 is provided with a straight groove 19. By straight groove is meant one of uniform cross-section throughout its length. This groove is so placed that its lower edge 20 will, when the blade is seated in the slot 4, substantially coincide with the edge 17 of the taper groove. It will be evident from a study of Figure 6 that when the blade 6 is seated in its slot and the pin 14 driven into the groove 16, the pin will bear against the lower edge 20 of the groove 19 in the blade, and the pin will also bear against the upper surface of the taper groove. Since this

upper surface is at an angle with the edge 20, a wedging action will take place tending to force the blade 6 downwardly and firmly to seat the same against the bottom 5 of the slot 4. At the same time this wedging action will have an angular component tending to force the blade 6 against the side of the slot. Since the pin 14 engages the edge 20 through the entire length of the 10 pin, a firm holding action will be obtained and the blade will be seated along its entire length. Since, however, the pin is supported in its groove 16, the fit can be so made; that while the blade is firmly supported, nevertheless it may be adjusted by the adjusting ring or collar 10, while the pins remain in position and act as guides for the blades.

Thus the taper grooves in the head 1 match 20 with the grooves 19 in the slot 6 when the blades are in place in their slots and this matching takes place in such a way that the lower edges 17 and 20 substantially coincide so that the pin 14, upon being driven into 25 the taper slot, will engage the blade 6 along an extended portion of the pin, that is, throughout practically its entire length and along a line parallel with the seat of the blade 6. The position of the edges 17 and 20 is such that their relation to each other is not altered by movement of the blade along the slot and up the inclined bottom 5. At the same time the pins 14 provide effective holding elements for holding the blades in their seats in whatever adjusted position the blades may be.

At the end of each taper groove, a drift receiving recess 21 is provided in the head 1. This recess provides access to the tip of the 40 pin 14 so that the same may be dislodged by inserting a drift in the recess 21 so that the blade may be removed or replaced.

It will be evident, therefore, that this invention provides a simple and effective reaming tool and one which can be easily and 45 positively adjusted and retained in adjusted position. The adjusting ring 10 may be worked along the thread 9 so as to move the blades along the slots and up the inclined

bottom 5 in order to expand the blades. 50 When proper adjustment has been obtained, the backing ring 12 may be tightened so that the blades will remain in adjusted position. The pins may easily be loosened by inserting a drift in the recess 21, when the blades are 55 to be removed.

It is obvious that various changes may be made in details of construction without departing from the spirit of this invention; it is, therefore, to be understood that 60 this invention is not to be limited to the specific details shown and described.

Having thus described the invention, what is claimed is:

1. An expansion reamer comprising, a 65 head having inclined slots therealong, blades adjustable in said slots, taper grooves in said head and matching with corresponding straight grooves in and along said blades, each pair of matching grooves intersecting 70 along a line parallel with the bottom of its respective slot, and a taper pin in each pair of matching grooves and bearing against the walls thereof, adapted to seat said blades in said head. 75

2. An expansion reamer, comprising, a head having inclined slots therealong, blades adjustable in said slots, straight grooves in and along said blades, taper grooves in said head matching said straight grooves but inclined thereto and intersecting along a line 80 parallel to the respective seats, and a taper pin in each pair of matching grooves adapted to guide said blades for adjustment.

3. An expansion reamer comprising, a 85 head having inclined slots therealong, blades adjustable in said slots, the blade having a straight groove parallel to the bottom of the slot for said blade, the side of the slot having a tapered groove with the portion 90 intersecting the groove in the blade coinciding therewith, and a tapered pin bearing where it contacts with the tapered groove along its full length.

In testimony whereof I affix my signature 95 this 1st day of September, 1922.

EMERY E. DAVIS.
